UNITED STATES PATENT OFFICE.

AUGUST H. R. HELLER, OF PITTSBURGH, PENNSYLVANIA.

SHOE-SHINING MACHINE.

1,138,868.

Patented May 11, 1915.

Application filed June 14, 1913. Serial No. 773,626.

To all whom it may concern:

Be it known that I, AUGUST H. R. HELLER, citizen of the United States, residing at Pittsburgh, in the county of Allegheny and 5 State of Pennsylvania, have invented certain new and useful Improvements in Shoe-Shining Machines, of which the following is a specification.

The present invention relates to improvements in shoe shining machines.

The primary object of the invention is the provision of a device of this character which will be simple in construction and operation and efficient for its purpose.

15 The invention consists essentially in the combination and arrangement of parts as hereinafter described involving a suitably operated machine, embodying a reciprocating carriage carrying brushes by means 20 of which polish furnished to the shoe may be brushed to shine the shoe. The machine is designed to operate on the shoes successively, and the brushing of the two shoes successively is accomplished by a motor 25 which actuates the machine during a predetermined number (sixteen) reciprocations of the traveling carriage. The motive power is cut off at the end of the sixteenth reciprocation of the carriage by actuating mechanism, 30 and the brushes which are moved to polishing position to operate on the shoe, are also removed from operative position by mechanism actuated at the end of the sixteenth reciprocation of the carriage. These and 35 other features will be more clearly set forth in the accompanying specification and drawings.

In the accompanying drawings: Figure 1 is a plan view of a machine embodying my 40 invention, the motor being omitted for convenience of illustration. Fig. 2 is a rear end view of the machine (as seen from the right in Fig. 1) showing the motor and driving mechanism. Fig. 3 is a vertical, longitudinal, sectional view of the machine. Fig. 4 is an enlarged detail elevation of the device for holding apart the front brushes. Fig. 5 is a plan view on line 10—10 Fig. 9 showing the brush holders and their separation means. Fig. 6 is a detail of the means for elevating the toe-brush. Fig. 7 shows the connection of an actuating rod to the reciprocating carriage by which the movement of the carriage is governed. Fig. 8 is a view showing in a general way the driving means for one of the brushes. Figs.

9 and 10 are fragmentary views of devices which assist in the actuation of one of the ratchet wheels.

The polishing machine is supported upon 60 a frame or base 1 from which rise the rear supports 2, 2 for the motor 3. The motor actuates the two driving shafts 4, 5, which are journaled in bearings 6 and extend longitudinally from end to end of the frame. 65 The shafts are revolved away from the center of the machine, *i. e.* shaft 5 revolves clockwise, and shaft 4 revolves anti-clockwise, and this motion is accomplished through the sprocket chain 7 which passes 70 over the sprocket 8 on the shaft 9 of the motor, and over large sprockets 10 and 11 on shafts 4 and 5 respectively. An idle sprocket 12 is employed to guide the chain over the wheel 10 as shown clearly in Fig. 2. 75

A reciprocable carriage 13 is supported, by the perforated ears or lugs 14, upon the shafts 4 and 5 and the carriage is free to slide on these shafts. The carriage is reciprocated by a crank rod 15 which is pivotally connected to the pedestal 16 on the carriage frame and at its other end is pivoted at 17 to the crank wheel 18 mounted on a stud shaft 19 journaled in the stationary frame of the machine. The crank wheel has 80 teeth 20 on its periphery meshing with the worm 21 on the shaft 5. From this description the transmission of the rotary motion of the shafts to the reciprocating motion of the carriage will be evident. The carriage 85 is intended to reciprocate a set of brushes in operative relationship to a shoe placed on the foot rest 22 which is stationary in the frame 1 of the machine. The carriage also carries a tank as 23, 24, one at each side and in 90 operative relationship to the foot rest. These tanks contain liquid blacking and are provided with pipes as 25 equipped with a nozzle 26 from which the liquid blacking may be sprayed on the shoe as the carriage 95 reciprocates, in determined manner and quantities. A stationary tank 27 is shown at the front of the machine which has the pipe 28 and nozzle 29 for spraying the heel 100 of the shoe. These nozzles, the movable ones and the stationary one, furnish liquid blacking or polish to the shoe that is supported on the foot rest, and the shoes are shined or polished by friction from the brushes for this purpose. These brushes 105 comprise a pair of heel brushes 30, 30' that are relatively movable horizontally, a pair

of toe brushes 31, 31', and a single toe brush 32 that is movable vertically to adapt itself to the front of the toe of the shoe to be shined. The brushes are revolved from the two shafts 4 and 5, and as each brush of each pair is driven in similar manner, a description of one driving means will suffice for all four. A bevel gear 33 on the horizontal driving shaft engages a horizontally disposed bevel gear 34 on the vertical shaft 35, and this shaft 35 bears a sprocket wheel 36 which is connected by chain 37 with the similar wheel 38 on the vertical shaft 39 upon which the brush is carried, and through these described connections the brush is revolved. The vertical shafts 35 and 39 transmit the power to the brushes, the shaft 39 being supported in a bracket 40 which is supported to oscillate on the shaft 35, the latter being revoluble in the carriage frame and acting as a pivot for the bracket as well. The brushes of each pair are urged toward each other by suitable means, and the brushes of at least one pair (the heel pair) are forced apart after eight reciprocations of the carriage, in order to permit the withdrawal of the shoe from the foot rest 22. This action is accomplished by mechanism clearly disclosed in Figs. 4 and 5, (see also Fig. 1) wherein two plates 41 are illustrated on the brush bracket or holder 40. These plates are positioned to act as cams, and move in the path of a pair of bolts or tappets 42 located adjacent the stem 43 upon which the foot rest 22 is supported. This stem is fixed in the frame 1 of the machine, but is revoluble and carries a toothed disk or wheel 44 provided with a cam lug 45 on its upper face. This lug is adapted to lift the bar 46 which carries the tappets 42, at certain predetermined intervals, *i. e.* at the end of eight reciprocations of the brush carriage, and this is accomplished by a pawl 44', 45 and 45^a and hook 46' (Fig. 5) pivoted on the carriage which engages one of the sixteen teeth of the wheel 44 on each return movement of the carriage to the front. The eight successive engagements of the pawl 44' and hook 46' with the toothed disk 49 revolves the disk so that its lug 45 comes in contact with the lug 47 on the bar 46 and this contact of lugs lifts the bar 46.

The bar 46 is vertically slidable and on its under face has a lug 47 in the path of movement of the lug 45, so that when the wheel 44 is revolved step by step the cam lug 45 finally engages the lug 47. The engagement of these lugs lifts the bar 46 with its tappets 42 against the tension of a flat spring 48 which bears against the under face of a plate 49 which is perforated for the passage of the two tappets. The engagement of the parts 41 with the tappets 42 distends the brush holders or brackets as

will be understood, and they are held distended until the two cams 45 and 47 pass out of contact which will be when the hook 46 engages the toothed wheel 44 on the next reciprocation of the carriage. It will be understood that this movement takes place at the end of each eight reciprocations of the carriage in order to permit the withdrawal of the shined shoe.

The brush 32 is revolved from the bevel gear 33 (dotted Fig. 1) on shaft 4, which engages a similar wheel 51 on shaft 52 carrying the sprocket wheel 53, and this wheel is connected by chain 54 to a similar wheel on shaft 55. This countershaft 55 has a sprocket that is connected by chain 56 to a sprocket on shaft 57, and the shaft 57 has a sprocket which is connected by chain 58 to a similar sprocket on the brush shaft 59.

The brush shaft 59 is journaled in a pair of swinging brackets 60 which are connected by a tube or sleeve 61 over the shaft 57. The housing 60' (which is a part of the arm 60) has a stud or screw 60^a secured thereon in path of movement of a lug 60^b rotatable with the sleeve 61, see Figs. 1 and 6. The brackets 60 are provided with downwardly extending arms 62 which are pivoted at 63 to the carriage frame 13. The brackets are adapted to oscillate on the sleeve 61 and shaft 57 to raise and lower the brush as the carriage reciprocates as follows:—A plunger rod 64 is pivoted at 65 to the arm 62 and the rod is supported to slide in the bracket 66 attached to the frame of the machine. A spring 67 is located on the plunger rod between a fixed collar 68 and the bracket 66, and at the other side of the bracket a shock or buffer spring 69 is located between the bracket and a fixed collar 70 at the free end of the plunger. By this arrangement of the plunger, and the bracket 66 as the plunger reciprocates with the brush carriage the contact of the spring 67 with the bracket causes the oscillatable brush supporting frame to swing on its pivot 63 to elevate and depress the brush so that it will travel over the toe of the shoe from the lower point or tip of the sole up on top of the toe of the shoe to thoroughly brush the toe. When the brush carriage moves to the rear the rod 64 slides in its support 66 until the spring 67 contacts with the same. Then the spring gradually compresses until it has reached the limit of its movement when the collar 68 takes up the pressure, and as bracket 66 is rigid with the base of the machine, the rod 64 presses against the portion 65 and the whole supporting mechanism of brush 59 rotates about point 63. Then as the arm 62 swings it will be seen that the spindle 57 is lifted, allowing the brush 32 to rise higher on the shoe until lug 60^b contacts with stud 60^a. With the parts 62 and 57 at their highest elevation, the arm 60 can rotate about point 57, and

the brush 52 can then reach farther back in a horizontal direction on the shoe. Thus the combination of the device pivoted at 63 with the device pivoted at 57 enables the 5 brush to make a longer reach both vertically and horizontally.

A suitable device (not shown) is provided to control the motor 3 by means of a connecting tappet rod 97 that is actuated from 10 the bell crank lever 99 pivoted at 100 and in position to be moved by a projection 101 on the swinging brush frame 62. In this manner the bell crank is oscillated and the tappet rod 97 moved so that it will impart 15 motion to the motor governor with each reciprocation of the carriage.

The operation of the machine is as follows: The heel brushes are held apart as described by means of the contacting cams. 20 The patron places his shoe upon the foot rest and the motor is put in operation. The two driving shafts are revolved and with them all the brushes. The carriage is reciprocated and the liquid blacking spraying 25 devices are operated. The first reciprocation of the carriage permits the heel brushes to act on the shoe, and the eighth reciprocation cuts off the motor through the connection of the tappet rod 97. After the first 30 shoe is withdrawn the second shoe is now put in place, the motor is again operated, and the machine performs until the carriage has reciprocated eight more times, when the motor is again cut off by the action of the 35 tappet rod connection, and the machine is stopped.

Having thus fully described my invention, what I claim as new and desire to secure by Letters Patent is:—

40 1. The combination with a reciprocating carriage of a foot rest, a pair of brushes on the carriage, holders for the brushes, contact points on the holders, and means actuated by the reciprocating carriage to separate said brushes by means of the contact points.

45 2. The combination with a reciprocating carriage and brushes thereon of contact points carried by the brushes, a rack wheel supported in a stationary frame, means on the carriage for turning said wheel, and means projected by the turning wheel into the path of the contact point to separate the brushes.

50 55 3. The combination with brushes as de-

scribed of a frame and a rack wheel supported thereon, a traveling carriage supporting the brushes having a pawl adapted to engage the wheel, and means upon the carriage projected by the predetermined rotation of said wheel into the path of movement of the brush holders and operating to separate the brushes. 60

4. The combination with a supporting frame, a reciprocable carriage and brushes 65 carried thereby, a rack wheel in the frame and a cam lug thereon, means for extending the brushes, including a plate having a lug complementary to the lug of the rack wheel, and a cam plate for each brush and means 70 on the first mentioned plate adapted to contact with said cam plates operating to separate the brushes.

5. The combination of a reciprocable carriage and a pair of separable brushes carried thereby, a supporting frame and a rack wheel journaled therein, means on the carriage for turning the wheel, a cam on the wheel, a perforated disk, a plate having a lug adapted to ride on said cam and a 75 pair of bolts on the plate adapted to pass through said perforated disk into the path of movement of the brush holders and operating to separate the brushes as described. 80

6. The combination with a pair of separable brushes having contact members of a supporting stem, a rack wheel on the stem having a cam lug, and means for revolving the wheel, a non-rotatable plate having a complementary lug adapted to ride on said 85 lug on the wheel, a perforated disk on the stem, a spring separating the plate and disk, and a pair of bolts carried by the plate adapted to pass through the perforated disk and engage said contact members to 90 separate the brushes. 95

7. The combination with a supporting frame bearing a perforated bracket, of a traveling carriage upon which is mounted a pivoted brush holder, a plunger rod 100 pivoted to the holder and passed through said perforated bracket, and a cushioning spring between the holder pivot and the bracket.

In testimony whereof I affix my signature 105 in presence of two witnesses.

AUGUST H. R. HELLER.
